UNITED STATES PATENT OFFICE

2,381,067

CONTAINER

Roy E. Lowey, Evanston, Ill., assignor to Container Corporation of America, Chicago, Ill., a corporation of Delaware

Application July 1, 1943, Serial No. 492,982

3 Claims. (Cl. 229—33)

This invention relates to paperboard containers, and more particularly to improvements in containers of the tuck-end type disclosed in Walter Patent No. 1,616,014, dated February 1, 1927.

One of the objects of the invention is to provide a collapsible box in which the ends are provided with slots or pockets and in which the top closure is provided with end extensions adapted to be readily and easily engaged in the slots or pockets to properly lock and hold the top closure in position.

Another object of the invention is to provide a knock-down box designed for packing relatively heavy materials which is readily and easily set up for use and which is capable of withstanding substantially the same loads as the non-collapsible tuck end container.

Another object of the invention is to provide a collapsible or foldable paperboard container which may be shipped or stored flat when not in use, and which may be readily and easily opened to receive articles to be packed or may be folded to its collapsible position.

Another object of the invention is to provide a collapsible cardboard folding container which is simple and inexpensive to manufacture.

Another object of the invention is to provide novel folding container and walls together with means for bracing the end walls when the container is in the set-up position whereby a strong and efficient structure will be had.

Further objects of the invention will be apparent from the following detailed description and the accompanying drawings, in which are set forth by way of illustration a preferred embodiment of the inventive thought.

In the drawings:

Fig. 1 is a plan view of a blank from which a container according to the invention is adapted to be formed;

Fig. 2 is a perspective view of the container formed from the blank of Fig. 1 after being set up but with the closure panels still open;

Fig. 3 is a perspective view partly broken away illustrating the manner in which the container of Fig. 2 may be collapsed; and

Fig. 4 is a perspective view showing the container of Fig. 2 completely collapsed for storage or shipping.

In the drawings reference numeral 10 denotes a bottom wall panel having two side wall panels 11, 11 connected thereto along score lines 12, 12. A cover panel 13 is connected to one of the side panels by means along score line 14 and an ex-

10 tension panel 15 is connected to the other side panel along score line 16.

The bottom wall panel 10 is connected to end walls or panels 10a along score lines 17, and the side walls 11, 11 are likewise provided with end flaps 11a, 11a connected thereto along score lines 18, 18. The cover panel 13 is provided with lateral extensions 13a, 13a hingedly connected to the cover panel along score lines 30. The end flaps 11a, and the ends of the side walls are separated from the end walls 10a by means of slots 19, 19.

In accordance with the present invention each of the end flaps 11a are provided with a score line 20 parallel to the score line 18 which connects the end flap to the corresponding side wall 11. The score line 20 divides each end flap into a relatively narrow portion 21 adjacent the side wall and the wider portion 22 extending from the score line to the end of the flap. When the carton is set up the narrow portions 21 of the end flaps are secured to the end walls in any suitable manner, as by staples 27 as indicated in Figs. 2 and 3. The end walls 10a are provided with diagonal score lines 23, which lines extend upwardly and inwardly at substantially 45° angles from the lower corners of the end walls. These score lines provide foldable triangular shaped wing portions 24, 24 at the outer edges of the end walls 10a. The extensions 13a, 13a of the cover panel 13 have their outermost corners cut away at 25, 25 and also have portions 26, 26 cut from their opposite free corners, which cut away portions are at least as wide as the securing portions 21 of the end flaps 11a.

To set up the container, the side walls 11 are first folded upwardly on the score lines 12 and the end flaps 11a are folded inwardly about the score lines 18, after which the end walls 10a are folded upwardly and are secured to the narrow rectangular portions 21 of the end flaps 11a by stapling or otherwise. This leaves the relatively wider portions 22 of the end flaps free to be grasped by the hands of the operator when it is desired to collapse or set up the carton. It will be noted that a portion of the end flaps 11a extend upwardly beyond the upper limit of the end walls or panels 10a, thereby rendering the upper part of portions 22 readily accessible. To collapse the container the portions 22 are pulled inwardly as indicated in Fig. 3, thereby allowing the end panels 10a to be collapsed along the diagonal score lines 23 so that the main body of the end flap 10a rests upon the bottom panel with the triangular wings 23 folded thereupon and with the end flaps 11a and side panels 11 folded

thereover as indicated in Figs. 3 and 4. Preferably the tucking extensions 13a are folded inwardly against cover panel 13 to produce the compact form shown in Fig. 4. The container is then in condition for storage or shipping.

When it is desired to set the container up for packing purposes it is only necessary to fold any two opposing panels outwardly to a vertical position and swing the portions 22 to positions adjacent end walls 10a so that the container cannot return to its collapsed position. After the container has been packed, the extension panel 15 is folded inwardly along score line 16 to a horizontal position and the cover panel 13 with the lateral extensions or tuck portions 13a, 13a is folded along the score line 14, the lateral extensions 13a, 13a fitting into the pockets formed between the wall portions 22, 22 of the end flaps 11a and the end wall 10a, thus securing rigidity for the assembled container. It will be noted that the cut-out portions 26 are wide enough so that the flaps 13a, 13a readily fit into the pockets even though the portions 21, 21 of the end flaps are permanently secured to the end walls. Finally the cover is secured in place by tape or in any other suitable manner.

The invention has been described in detail for the purpose of illustration, but it will be obvious that numerous modifications and variations may be resorted to without departing from the spirit of the invention.

I claim:

1. In a collapsible container formed from a single blank of sheet material, a bottom wall, side and end walls formed on said bottom wall and movable thereover when said container is in a folded condition, said end walls having foldable triangular-shaped wings on their outer edges, and wall flaps formed on the end edges of said side walls having creases therein substantially parallel to said end edges defining rela-

tively narrow securing strips carried by said side walls and foldable outer portions, and means firmly connecting said securing strips with and in underlying relation to said wings.

5. The combination according to claim 1 including a cover formed on the upper edge of one of said side walls and cover extensions formed on the side edges of said cover adapted to be inserted between said end wall flaps and between said securing means.

10. 3. A collapsible container formed from a single blank of relatively heavy paperboard such as solid fiberboard or the like comprising a bottom wall, side and end walls formed on said bottom wall and foldable thereover when said container is in a collapsed condition, said side walls having somewhat greater height than said end walls and each of said end walls including a pair of foldable triangular-shaped wings defined by the side and upper edges thereof and a pair of fold lines at an angle of approximately 45° from said bottom wall converging from the lower corners thereof, substantially rectangular end wall flaps formed on the end edges of said side walls having substantially the same height as said side walls, each of said flaps having a fold line therein substantially parallel to said end edges and defining a relatively narrow securing strip carried by a side wall and a foldable outer portion, means firmly connecting each of said securing strips in underlying relation to one of said wings adjacent its side edge, a cover formed on the upper edge of at least one of said side walls, and cover extensions formed on the side edges of said cover, 15 each of said extensions being adapted to be inserted between one of said end walls and the end wall flaps associated therewith and between said securing means when said cover is in closed position.

40

ROY E. LOWEY.
